DESIGN FOR A DRINKING GLASS

Charles Meissirel Marquot, Paris, France

Application July 14, 1934, Serial No. 52,583

Term of patent 7 years

To all whom it may concern:

Be it known that I, Charles Meissirel Marquot, a citizen of the Republic of France, residing in Paris, France, and whose post-office address is 22 bis, Rue de Paradis, have invented a new, original, and ornamental Design for Drinking Glasses, of which the following is a specification, reference being had to the accompanying drawing, forming part thereof.

In said drawing Fig. 1 is a front elevation and Fig. 2 is a perspective view of a drinking glass showing my new design.

Fig. 3 is a longitudinal cross section on a reduced scale showing the contour of the inside paneling.

The bottom of the glass is substantially square and the top circular, and the dotted lines show the contour of the interior of the glass coming down to a rounded point.

I claim:

The ornamental design for a drinking glass, as shown and described.

CHARLES MEISSIREL MARQUOT.
